UNITED STATES PATENT OFFICE.

ALFRED L. ATHERTON, OF PITTSBURGH, PENNSYLVANIA, ASSIGNOR TO WESTINGHOUSE ELECTRIC & MANUFACTURING COMPANY, A CORPORATION OF PENNSYLVANIA.

LIGHTNING ARRESTER.

Application filed January 24, 1921. Serial No. 439,393.

To all whom it may concern:

Be it known that I, ALFRED L. ATHERTON, a citizen of the United States, and a resident of Pittsburgh, in the county of Allegheny and State of Pennsylvania, have invented a new and useful Improvement in Lightning Arresters, of which the following is a specification.

My invention relates to protective devices and it has particular relation to lightning arresters of the multiple-gap type that are enclosed in casings and adapted for outdoor service, the casings operating also, to protect or shield the active elements thereof from unauthorized and improper interference when in a charged condition.

Heretofore, it has been customary to construct the non-arcing conducting members in the form of knurled cylinders adapted to effect a point discharge between the respective members in the event of a surge of potential in the line. Should a device provided with conducting members of the above type be frequently subjected to the destructive effect of heavy discharges, the knurled surfaces of the members soon became so pitted or otherwise deformed as to necessitate the replacement thereof.

One of the objects of my invention is to provide a device of the above indicated character in which the conducting members comprise relatively inexpensive machine screws of standard sizes, and preferably of a non-arcing metal, so arranged that the threaded body portions thereof perform the same function as the knurled cylinders heretofore employed, thereby materially reducing the expense of repairs.

Another object of my invention is to so dispose or interleave the electrodes as to increase the creepage distance therebetween.

Another object of my invention is to provide a lightning arrester of the above indicated character that shall be simple in construction, economical in manufacture, and reliable in operation and one that shall be protected or shielded against inadvertent or intentional interference by unauthorized persons and, at the same time, be so designed that the accessible parts thereof shall be thoroughly insulated from one another and the active elements adequately protected against all weather conditions.

In the accompanying drawings,

Figure 1 is a plan view of a lightning 55 arrester embodying my invention.

Fig. 2 is a vertical longitudinal section taken on line II—II of Fig. 1, and illustrating the arrangement of the screw-threaded 60 conducting members.

Fig. 3 is a vertical transverse sectional view taken on line III—III of Fig. 2.

Referring to the drawings, a lightning arrester embodying my invention is illustrated as comprising an outer casing 1, 65 preferably constructed of insulating material, such as porcelain, for example, and consisting of a top 2, end portions 3 and side walls 4 and being open at the bottom, as indicated at 5. The top or upper portion 2 of the casing 1 may be provided with a lug or extension 6 adapted to be secured to a pole, cross-arm or other suitable supporting structure.

An inner casing 7 is telescopically disposed within the casing 1 and comprises end walls 8, a single side wall 9, and a top and a bottom 10 and 11, respectively. The casing 7 is open on one side, as indicated at 12, by means of which access may be readily had to the interior thereof. The casing 7 is inserted within the casing 1 through the opening 5 at the bottom thereof and, when in place, the open side 12 is closed by the side wall 4 of the outer casing 1. Suitable 85 means, such as pins 13, may be provided to prevent the casing 7 from becoming accidentally displaced.

It will be apparent from the foregoing that the outer casing 1 tends to shed rain 90 or protects it from the weather and prevents the same from leaking into the inner casing 7.

The conducting members preferably comprise a plurality of machine screws 14 of 95 non-arcing material disposed in a vertical longitudinal plane and alternately mounted in the top and bottom walls 10 and 11 of the casing 7 to extend in opposite directions and in spaced and parallel relation with respect to each other.

The heads of the screws 14 are so disposed within the recesses 15 as to lie flush with the outer surface of the inner casing 7. The screws are preferably retained in place by 105 means of lock nuts 16 abutting against the

inner surfaces of the walls 10 and 11, respectively.

A resilient contact member 17 is secured to one of the screws 14 and extends upwardly through an aperture 18 in the end wall 8 and yieldably engages a line terminal 19. The end wall 8 of the casing 7 is provided with a slot 20 within which the terminal 19 extends. The upper extremity 10 of the contact member 17 is formed with an inwardly inclined portion 21 which provides a cam surface for engagement with the terminal 19 when the casing 7 is inserted into the casing 1.

15 The conducting element 14, at the opposite end of the series, is connected, by means of a copper strip 22, to a spring clip or terminal 23 which is also mounted upon the bottom 11 of the inner casing 7. A 20 second spring clip 24, in alignment with the clip 23, is positioned adjacent to the other end of the casing 7 and is connected to the clip 23 by a resistance rod 25, of any suitable material having a high specific resistance.

The clip 24 is connected to a resilient contact member 26, similar in construction to the member 17, and extends through an opening 27 in the end wall 8 for yieldable engagement with a ground terminal 29 which is mounted in the end wall 3 of the outer casing. The member 26 may also be provided with an inclined portion 30 adapted to engage the terminal 29 and be forced inwardly, when the inner casing 7 is disposed in place. A channel 31 may be provided in the wall 8 of the inner casing and within which the ground terminal may project.

40 It will be apparent that the threaded body portions of the adjacent screws 14 effect a point discharge between the respective electrodes in a manner similar to the knurled surfaces of the cylinders hereunto employed and, at the same time, being relatively inexpensive and are readily interchangeable.

I claim as my invention:

1. An electrode for lightning arresters having a threaded discharge surface. 50

2. A protective device comprising a plurality of spaced electrodes having threaded discharge surfaces.

3. A protective device having a plurality of electrodes arranged to form a spark gap 55 and provided with screw-threaded portions adapted to effect point discharges between said electrodes.

4. A protective device comprising a plurality of electrodes having threaded discharge surfaces arranged in spaced and 60 parallel relation within a single plane.

5. A protective device comprising a plurality of electrodes having threaded discharge surfaces arranged in spaced and 65 interleaved relation.

6. A protective device comprising a plurality of electrodes having threaded discharge surfaces arranged in spaced and 70 parallel relation and extending alternately in opposite directions with respect to each other.

7. A protective device comprising a plurality of electrodes having threaded discharge surfaces arranged in spaced and 75 parallel relation, and alternately extending in opposite directions in overlapped relation with respect to each other.

8. A protective device comprising an outer casing, an inner casing telescopically mounted in said outer casing, a plurality of electrodes mounted in said inner casing, a resistance element connected in series with said electrodes, a plurality of terminals mounted in the walls of said outer casing and a plurality of resilient contact members connected to said electrodes and to said resistance element, respectively, for yieldable engagement with said terminals. 80

85 In testimony whereof, I have hereunto subscribed my name this 17th day of January 1921.

ALFRED L. ATHERTON.
